UNITED STATES PATENT OFFICE.

HERBERT O. RUSSELL, OF SANTA ANA, CALIFORNIA, AND CHARLES L. PAULUS,
OF DAYTON, OHIO.

HOPPER FEED BOX FOR MACHINE GUNS.

Refile of abandoned application Serial No. 555,421, filed April 18, 1922. This application filed November 16, 1925. Serial No. 69,537.

This invention relates to hopper feed boxes for machine guns. The object of the invention is to provide a feed box capable of being readily fastened to and detached from a machine gun for the purpose of feeding ammunition to any type of machine gun which is designed to be fed by means of a belt. The improved hopper feed box provides means for properly feeding ammunition into the feed way of a machine gun when the ammunition is carried in the box in a loose condition.

With the above and other objects in view the invention consists in the novel construction, combination and arrangement herein 15 fully described, illustrated and claimed.

In the accompanying drawings—

Fig. 1 is a fragmentary side elevation in dotted lines of a machine gun showing the 20 hopper feed box mounted thereon.

Fig. 2 is a top plan view of the same.

Fig. 3 is a sectional view through the hopper feed box taken at a right angle to Figure 1.

Referring to the drawings, 1 designates the hopper feed box which is generally cylindrical. In order to fill the box with cartridges, the box is provided with a lid or door 2 connected at its opposite ends by 25 means of hinge knuckles 3, and hinge pins 4 to the box 1, each of the pins 4 having at one end thereof a handle 5 of any suitable shape.

The lower portion of the box 1 is formed with a right angular cut away portion 6 in 30 order to adapt it to fit over the cover plate of the gun indicated at 7, and as shown in Figure 3. Along the bottom wall 8 of the box 1 extends a plate 9, having out turned flanges 10, which are adapted to slide under 35 the inturned flanges 11 of another guide plate 12. The plate 12 is carried by a mounting bracket or plate 13 fastened at one end to the gun by means of a pin 14, and fastened at its opposite end to the cover plate 40 of the gun by means of a locking bolt or pin 15, having at the other end thereof an operating lever 16. The construction just designated provides for readily detaching the box 1 from the mounting plate or bracket 13, 45 and also detaching the latter from the gun.

In order to lock the hopper feed box on the gun, we provide a catch 17 which is connected at one end to the box by means of a pivot 18, and pressed outwardly by a spring

19. The outer projecting end of the catch 55 17 has attached thereto one end of a flexible strap 20 which extends upwardly under one of the hinge pins 14 over the top of the box 1 where it forms a carrying handle 21. The operator, by placing his hand over the top 60 of the box 1 and pressing upwardly with the back of his hand under and against the strap 21, is able, with the aid of one hand only, to operate and trip the catch 17, unlocking the box from the gun and remove 65 the box entirely from the gun. By reversing the operation just described, he is able to place another box on the gun and lock the same in place.

The box 1 is formed at the lower-most 70 part thereof with a cartridge outlet 22. In conjunction with said outlet, we employ a vertically slidable shutter 23 which is normally pressed to a closed position by means of an expansion spring 24. Connected to 75 the shutter 23 by means of a pivot 25 is a cam lever 26, having a cam face 27 which is acted upon by the plate 12 as the box is slid across the top of the gun, the camming action resulting in raising and opening the 80 shutter 23 so that the cartridges contained in the box 1 may pass into the feed-way 28 of the gun.

Operating within the feed box 1 is a spring actuated follower 29, the same being 85 disposed radially with respect to the center of the feed box 2. Said follower 29 has one or more arms 30 at the inner end thereof which are journaled on a center shaft 31 extending through the side walls of the box 1. 90 A helical spring 32 encircles the shaft 31, and serves to press the follower 29 from left to right in Figure 3 for the purpose of urging the cartridges around the interior of the box 1 toward the discharge outlet 22 where 95 they are acted upon by the feed pawls 33 and 34 of the gun.

Adjacent to and working along the top of the outlet 22 is a normally horizontal sliding separator 35 which is attached to and 100 actuated by the feed slide 36 of the gun. The separator 35, by working back and forth, prevents jamming of the cartridges as they approach the outlet 22 and lines said cartridges up in readiness to pass out through 105 said outlet. 37 designates a spring housing plate detachably fastened to one of the side walls of the box 1 by any suitable means so

that it may be removed to give access to the spring 32 for any desired purpose.

We claim:

1. A machine gun having a guideway extending transversely thereof, in combination with a hopper feed box adapted to be connected to and disconnected from the gun by movement along said guideway, a gate controlling the cartridge outlet of said box, and 10 cam operated means for opening said gate as the box is slid into operative relation to the gun.

2. A machine gun having a guideway extending transversely thereof, in combination 15 with a hopper feed box adapted to be connected to and disconnected from the gun by movement along said guideway, and a manually operable catch for locking the hopper feed box to the gun, a spring closed gate 20 controlling the cartridge outlet of said box, and cam operated means for opening said gate as the box is slid into operative relation to the gun.

3. A hopper feed box for machine guns 25 comprising a generally cylindrical body hav-

ing an elongated cartridge outlet, a spring actuated follower therein to advance the cartridges toward said outlet, a mounting bracket for said box secured to the gun, a shutter for said outlet, and means to automatically open and close said shutter as the box is placed upon and removed from said mounting bracket, said means embodying a cam lever on the box adapted to contact with the mounting bracket. 35

4. A hopper feed box for machine guns comprising a generally cylindrical body having an elongated cartridge outlet, a spring actuated follower therein to advance the cartridges toward said outlet, a mounting 40 bracket secured to the gun, a catch on the box to engage said bracket, and a box carrying handle consisting of a flexible strap connected with said catch and adapted to release the latter when subjected to stretching action by the hand of the operator. 45

In testimony whereof we affix our signatures.

HERBERT O. RUSSELL.
CHARLES L. PAULUS.
